US00D691119S

(12) **United States Design Patent**
Manhard et al.

(10) **Patent No.:** **US D691,119 S**
(45) **Date of Patent:** **** Oct. 8, 2013**

(54) **EARPIECE**

(75) Inventors: **John L. Manhard**, Durham, NC (US);
Matthew J. Morton, Holly Springs, NC (US)

(73) Assignee: **Scion NeuroStim, LLC**, Raleigh, NC (US)

(**) Term: **14 Years**

(21) Appl. No.: **29/424,947**

(22) Filed: **Jun. 18, 2012**

(51) **LOC (9) Cl.** **14-01**

(52) **U.S. Cl.**

USPC **D14/223**

(57) **CLAIM**

The ornamental design for an earpiece, as shown and described.

DESCRIPTION

FIG. 1 is a front left perspective view of a first embodiment of an earpiece showing our design;
FIG. 2 is a left side view thereof;
FIG. 3 is a front view thereof;
FIG. 4 is a right side view thereof;
FIG. 5 is a rear view thereof;
FIG. 6 is a top view thereof;
FIG. 7 is a bottom view thereof;
FIG. 8 is a back right perspective view thereof;
FIG. 9 is an environmental view of the first embodiment of an earpiece showing our design;
FIG. 10 is a front left perspective view of a second embodiment of an earpiece showing our new design;
FIG. 11 left side view thereof;
FIG. 12 is a front view thereof;
FIG. 13 is a right side view thereof;
FIG. 14 is a rear view thereof;
FIG. 15 is a top view thereof;
FIG. 16 is a bottom view thereof;
FIG. 17 is a back right perspective view thereof; and,
FIG. 18 is an environmental view of the second embodiment of an earpiece showing our new design.
The broken lines shown herein are for illustrative purposes only and form no part of the claimed design.
